UNITED STATES PATENT OFFICE

JAMES E. TAYLOR, OF CLEVELAND, OHIO

DEVICE FOR LOCKING SCREEN DOORS AND THE LIKE

Application filed October 22, 1928. Serial No. 314,016.

This invention relates to locking devices, particularly those which are commonly used for locking screen doors, window screens and the like. One form of device heretofore used for this purpose has embodied a single hook member, which is usually fastened upon the screen or door and is adapted to engage an eye member upon the door or window jamb. It is an easy matter for locks of this nature to be opened by unauthorized persons merely by the insertion of a tool through the screen and by raising the hook member out of contact with the co-operating eye member.

An object of my invention is to make a locking device which may be incorporated in a type of window screen or door lock of the form described, and which will prevent opening of the lock in the manner set forth. A further object of my invention is to make a locking device which will open only when operated in a predetermined manner. The intention of this provision is to minimize the possibility of an unauthorized person tearing the screen for a short distance near the lock, and then endeavoring to lift the hook out of engagement with the cooperating eye.

A further object of my invention is to make a locking device which is simple in construction and which may be readily made and easily operated when in use.

Referring to the drawings, Fig. 1 is a perspective view of a screen or door which is locked by the device embodying my invention; Fig. 2 is a perspective view of the locking device removed from the screen, and showing the locked position thereof; Fig. 3 is a side elevation of the lock showing the keeper in two different positions; Fig. 4 is a side elevation of the lock in closed position; and Fig. 5 is a top plan view of the lock.

The preferred form of my invention comprises a hook member 10 and a keeper 11, which is slidable along the hook and which cooperates with an arm 12 to lock the hook in place. The hook and arm, as shown, are made of a single piece of wire, which is bent to form a loop 13 through which a fastening member 14 may extend for securing the hook to a screen or door 15. The elasticity of the wire

permits the arm to be moved slightly with reference to the hook whenever desired. Such movement is sufficient for enabling the hook to be passed through an eye 16 in the door or window jamb as is shown in Fig. 1.

The open position of the keeper is illustrated by the full lines of Fig. 3 where the hook and arm are illustrated as being moved apart a sufficient distance to clear the locking eye. After the hook is placed over the eye, the keeper is moved forwardly to a position shown at 11a by the broken lines in Fig. 3.

The keeper, as illustrated, is made from a single piece of wire bent to the shape of a figure 8. The hook member has a notch 20 into which the top loop of the keeper may extend and the arm 12 is also shown as having a notch 21 on the underside thereof into which the bottom loop of the keeper may extend. The notch 21 is in a re-entrant portion 22, which is formed by bending the arm first outwardly, as at 23, then inwardly as at 24, and then outwardly again as at 19. The arm thus has a substantial hump or shoulder over which it must pass before it can be withdrawn to the open position. Moreover such hump prevents the lock from being opened merely by forcing the keeper backwardly along the hook. Notches 30 and 31 also function to assist in holding the keeper in position. To open the lock, it is necessary to press the arm and keeper slightly together, until the bottom part of the keeper falls out of the re-entrant portion 22. By making the notch 21 nearer to the end of the hook than the notch 20, the keeper occupies a position, when locked, extending obliquely to the direction of the hook. Thus, the action of gravity assists in making the keeper clear the hump, whenever the arm is pressed toward the hook while the door is locked. In locked position, the looped portion 25 at the end of the arm is sufficiently close to the end 26 of the hook, that the lock cannot be opened when shifting the keeper to the open position.

I claim:

1. A locking device comprising a strip of wire bent to provide two arms, a keeper slideable along the arms, each of said arms having a notch therein adapted to be engaged by the

keeper when the keeper is in locking position, said notches being offset with relation to each other, whereby the keeper extends diagonally to the arms when in locked position.

- 5 2. In a device of the character described, the combination with a single strip of wire bent intermediately to form a loop, and having two arms extending from the loop in the same general direction, the end of one of the arms being shaped to form a hook, and the end of the other of said arms being shaped to form an eye, into which the end of the hook extends, a member movable along said arms and being adapted to occupy one position when said arms are closed, and to occupy another position when said arms are opened, and means associated with said arms and acting upon the member for holding the arms in closed position, said means permitting movement of the keeper to open position when the arms are pressed together a predetermined distance.
- 10 3. A device of the character described, comprising in combination, a strip of wire bent intermediately to form a loop with two arms extending from the loop and in the same general direction, one of the arms having the end thereof shaped to form a hook and the other of said arms having the end thereof shaped to form an eye to receive said hook portion when the arms are moved toward each other, said last mentioned arm having that portion thereof near the eye curved in two directions
- 15 35 to make a re-entrant portion, a keeper slidable along the arms and being formed of a single strip of wire looped to engage each arm, one of the loops of the keeper being adapted to engage one arm behind the hook and to engage the other arm within the re-entrant portion for holding the arms in locked position.
- 20 4. A device of the character described, comprising a strip of wire bent to provide a pair of arms movable with relation to each other, one arm having a recess facing outwardly, the other arm having an outward bend providing a pair of shoulders spaced apart, and a keeper slidable along the arms and adapted to occupy said recess and swing about it as a center
- 25 40 50 into engagement with either of the shoulders of the other arm.

In testimony whereof, I hereunto affix my signature.

JAMES E. TAYLOR.
